COIL COMPONENT

CROSS REFERENCE TO RELATED APPLICATIONS

This application claims benefit of priority to Japanese Patent Application 2016-022350 filed Feb. 9, 2016, the entire content of which is incorporated herein by reference.

TECHNICAL FIELD

The present disclosure relates to coil components, and more particularly relates to a coil component including a drum-shaped core having a winding core portion around which a wire is wound and flange portions provided at both end portions of the winding core portion.

BACKGROUND

For example, there is a configuration described in Japanese Patent No. 4737268 as a technology of interest for the disclosure. Japanese Patent No. 4737268 describes the following pulse transformer as a coil component.

The pulse transformer described in Japanese Patent No. 4737268 includes a drum-shaped core having a winding core portion and first and second flange portions provided at respective end portions of this winding core portion. Each of the first and second flange portions has an inner end surface that faces the side of the winding core portion and positions the corresponding end portion of the winding core portion, an outer end surface that faces the outer side opposite to the inner end surface, a bottom surface that couples the inner end surface with the outer end surface and faces the side of a mount substrate at mounting, and a top surface opposite to the bottom surface.

For example, four wires are wound around the winding core portion of the drum-shaped core. Three terminal electrodes are provided at each of the first and second flange portions. The terminal electrodes are positioned on the bottom surface of each flange portion. End portions of two wires are connected with two terminal electrodes among the three terminal electrodes on each flange portion. End portions of the residual two wires are commonly connected with the residual one terminal electrode.

Also, a plate-shaped core is bridged between the first and second flange portions. One principal surface of the plate-shaped core is in contact with the top surface of each of the first and second flange portions.

Such a pulse transformer is used for transmitting a communication signal and obtaining electrical insulation.

SUMMARY

Particularly focusing on the drawings of Japanese Patent No. 4737268, the drum-shaped core illustrated therein has the following areal relationship. In particular, the first and second flange portions are shorter than the winding core portion, and the sum of the areas of contact portions which are included in the top surfaces of the first and second flange portions and which contact the one principal surface of the plate-shaped core is only about $\frac{1}{3}$ or smaller the area of an imaginary rectangle defined by four vertices on sides of the outer peripheries of the contact portions when FIG. 3 of Japanese Patent No. 4737268 is actually measured.

In particular, a drum-shaped core of a coil component having an existing structure in which the winding center axis of a wire is parallel to a mount substrate, represented by the

2

configuration described in Japanese Patent No. 4737268, typically has the above-described areal relationship for the following reasons.

First, a magnetic resistance generated by a gap unavoidably formed between the top surfaces of the flange portions and the one principal surface of the plate-shaped core is relatively large, and hence, magnetic efficiency in a closed magnetic path given by the drum-shaped core and the plate-shaped core becomes low. To compensate the aforementioned low magnetic efficiency and ensure a desirable inductance, it is required to increase the winding number of wire.

To increase the winding number of wire, the winding core portion has to be long. However, with the existing structure, the external dimension of the coil component is limited in view of mounting area. That is, the lengths of the flange portions are required to be decreased by the amount of the increase in the length of the winding core portion. Consequently, in a drum-shaped core having the existing structure described in many documents or being available in the market, the flange portions are shorter than the winding core portion, and in many cases, the drum-shaped core has the aforementioned areal relationship, in which the sum of the areas of the contact portions is about $\frac{1}{3}$ the area of the imaginary rectangle at its maximum.

However, as the winding number of wire increases, an interline capacitance generated between turns of the wire increases, and a resistance loss also increases. The inventor of this application has focused on high frequency characteristics of the coil component with the above-mentioned existing structure are consequently degraded. For example, with the existing structure, it may be difficult to realize high frequency characteristics desirable in the future, such as one complying with the standard of 10GBASE-T.

Accordingly, it is an object of the disclosure to provide a coil component that decreases the influence of a magnetic resistance generated by a gap between flange portions and a plate-shaped core, and hence can acquire a larger inductance without increasing the winding number of wire.

According to one embodiment of the present disclosure, a coil component includes a drum-shaped core including a winding core portion and first and second flange portions provided at respective end portions of the winding core portion along a predetermined direction. Each of the first and second flange portions has an inner end surface that faces a side of the winding core portion and positions the corresponding end portion of the winding core portion, an outer end surface that faces an outer side opposite to the inner end surface, a bottom surface that couples the inner end surface with the outer end surface and faces a side of a mount substrate at mounting, and a top surface opposite to the bottom surface.

The coil component according to the embodiment of the disclosure further includes a plate-shaped core bridged between the first and second flange portions while one principal surface of the plate-shaped core contacts the top surface of each of the first and second flange portions; at least one first terminal electrode provided on the bottom surface of the first flange portion; at least one second terminal electrode provided on the bottom surface of the second flange portion; and at least one wire wound around the winding core portion and connected between the first and second terminal electrodes.

In this coil component according to the embodiment of the disclosure a sum of an area of a first contact portion which is included in the top surface of the first flange portion and which contacts the one principal surface of the plate-

shaped core and an area of a second contact portion which is included in the top surface of the second flange portion and which contacts the one principal surface of the plate-shaped core is $\frac{2}{3}$ or larger a product of a third maximum width W and a maximum length L , in a case where, when a first maximum width of the first contact portion and a second maximum width of the second contact portion are maximum widths along a direction orthogonal to the predetermined direction, the third maximum width W is a smaller one of the first maximum width and the second maximum width, and in a case where, when an edge on the outer side of the first contact portion is a first outer edge and an edge on the outer side of the second contact portion is a second outer edge, the maximum length L is a maximum distance between the first outer edge and the second outer edge measured along the predetermined direction.

It should be understood that the configuration in which the sum of the area of the first contact portion and the area of the second contact portion is $\frac{2}{3}$ or larger the product of the third maximum width W and the maximum length L as described above is relatively significant for clear differentiation from the related art.

With the above-described configuration, since the contact area between the flange portions and the plate-shaped core can be largely ensured, a magnetic resistance which may be generated between the flange portions and the plate-shaped core can be decreased.

In the coil component according to another embodiment of the disclosure, the first and second contact portions may be typically substantially quadrangular although the first and second contact portions do not have to be substantially quadrangular. If the first and second contact portions are substantially quadrangular, the sum of the area of the first contact portion and the area of the second contact portion may be preferably $\frac{2}{3}$ or larger an area of an imaginary quadrangle defined by two vertices on a side of an outer periphery of the first contact portion and two vertices on a side of an outer periphery of the second contact portion.

If the first and second contact portions are substantially quadrangular as described above, in a perspective view in a direction orthogonal to a direction in which the principal surface of the plate-shaped core extends, an outer peripheral edge of the plate-shaped core may be preferably substantially aligned with edges of the imaginary quadrangle. With this configuration, the entire volume of the plate-shaped core can contribute to formation of a closed magnetic path, and this is efficient.

In the above-described embodiments, the first and second flange portions may be joined with the plate-shaped core, for example, by an adhesive. In this case, the adhesive may be preferably arranged to surround contact surfaces of the first and second contact portions of the first and second flange portions and the principal surface of the plate-shaped core, except for portions along the inner end surfaces. With this configuration, because the adhesive perimeter with the adhesive can be long, even if the adhesive is applied merely to surround the contact surfaces, a sufficient adhesive force can be ensured.

If the first and second contact portions are substantially quadrangular as described above, in a perspective view in a direction orthogonal to a direction in which the principal surface of the plate-shaped core extends, an outer peripheral edge of the plate-shaped core may be located inside the imaginary quadrangle, and hence an exposed portion exposed from the plate-shaped core may be provided at each of the top surfaces of the first and second flange portions.

In the aforementioned alternative embodiment, the first and second flange portions may be joined with the plate-shaped core, for example, by an adhesive. In this case, the adhesive may be preferably arranged to surround contact surfaces of the first and second contact portions of the first and second flange portions and the principal surface of the plate-shaped core, except for portions along the inner end surfaces while the adhesive contacts the exposed portions and side surfaces of the plate-shaped core. With this configuration, not only the adhesive perimeter with the adhesive can be long, but also the adhesive can be brought into contact with the two surfaces directed in mutually different directions in a cross section. Accordingly, a higher adhesive force can be obtained.

As described above, if the first and second flange portions are joined with the plate-shaped core by the adhesive, more preferably, the adhesive is not present on the contact surfaces of each of the first and second contact portions of the first and second flange portions and the principal surface of the plate-shaped core. With this configuration, since the state in which the flange portions directly contact the plate-shaped core can be provided, for example, as compared with a situation in which the adhesive is interposed, the magnetic resistance which may be generated between the flange portions and the plate-shaped core can be further decreased, and hence this may contribute to acquisition of a larger inductance.

According to another embodiment of the disclosure, at least one of the first and second terminal electrodes may be preferably arranged to extend from an end edge on a side of the outer end surface toward an end edge on a side of the inner end surface on the bottom surface of the first or second flange portion by a distance being half or smaller a distance between the outer end surface and the inner end surface. With this configuration, a relatively large space in which a terminal electrode is not present can be created near the winding core portion on the side of the bottom surface of the flange portions, that is, on the side of the mount surface. Also, the space in which a terminal electrode is not present near the winding core portion can be used as a buffer space that gives flexibility to the positions and orientations of the wires between an area on the winding core portion and an area on the terminal electrodes where the positions and orientations of the wires are fixed. Hence, the wires are not excessively forcedly deformed, and occurrence of a break or a short in the wires can be reduced.

According to another embodiment of the disclosure, a gradient surface or a step surface may be preferably formed on the side of the inner end surface on the bottom surface of at least one of the first and second flange portions. With this configuration, the space in which a terminal electrode is not present and which is formed on the side of the mount surface can be further widened, and shorter path can be given to each of the wires guided to extend from the end portion peripheral surfaces of the winding core portion to the terminal electrodes.

According to another embodiment of the disclosure, a flat property of the top surface of at least one of the first and second flange portions may be preferably higher than a flat property of another principal surface opposite to the principal surface of the plate-shaped core. Instead of this configuration or in addition to this configuration, a flat property of the principal surface of the plate-shaped core which contacts each of the top surfaces of the first and second flange portions may be preferably higher than the flat property of the other principal surface of the plate-shaped core. With this configuration, the degree of close contact

5

between the flange portions and the plate-shaped core can be increased, and a region where processing such as mirror-surface polishing is executed to increase the flat property can be minimized.

With the coil component according to the embodiments of the disclosure, the contact area between the flange portions and the plate-shaped core can be largely ensured and hence the magnetic resistance which may be generated between the flange portions and the plate-shaped core can be decreased. Hence, a large inductance can be acquired without an increase in the winding number of wire. Accordingly, since the increase in capacitance or resistance loss due to the increase in the winding number of wire does not occur, a coil component with good high frequency characteristics can be provided.

Other features, elements, characteristics and advantages of the present disclosure will become more apparent from the following detailed description of some embodiments of the present disclosure with reference to the attached drawings.

BRIEF DESCRIPTION OF THE DRAWINGS

FIGS. 1A to 1D show a coil component according to a first embodiment of the disclosure, FIG. 1A being a plan view, FIG. 1B being a front view, FIG. 1C being a bottom view, FIG. 1D being a right side view.

FIGS. 2A and 2B show a joint structure between a flange portion and a plate-shaped core of the coil component shown in FIGS. 1A to 1D, FIG. 2A being a front view, FIG. 2B being a cross-sectional view along line 2-2 in FIG. 2A.

FIGS. 3A to 3D show a coil component according to a second embodiment of the disclosure, FIG. 3A being a plan view, FIG. 3B being a front view, FIG. 3C being a bottom view, FIG. 3D being a right side view.

FIGS. 4A to 4D show a coil component according to a third embodiment of the disclosure, FIG. 4A being a plan view, FIG. 4B being a front view, FIG. 4C being a bottom view, FIG. 4D being a right side view.

FIGS. 5A and 5B provide comparison between a pulse transformer according to an example within a range of the disclosure and a pulse transformer according to a comparative example outside the range, FIG. 5A showing frequency characteristics of an insertion loss, FIG. 5B showing a measurement circuit for the insertion loss.

FIGS. 6A and 6B provide comparison between the pulse transformer according to the example within the range of the disclosure and the pulse transformer according to the comparative example outside the range, FIG. 6A showing frequency characteristics of a mode conversion, FIG. 6B showing a measurement circuit for the mode conversion.

FIGS. 7A and 7B provide comparison between the pulse transformer according to the example within the range of the disclosure and the pulse transformer according to the comparative example outside the range, FIG. 7A showing frequency characteristics of a common mode rejection ratio, FIG. 7B showing a measurement circuit for the common mode rejection ratio.

FIG. 8 is an illustration corresponding to FIG. 2A to explain a fourth embodiment of the disclosure.

FIG. 9 is an illustration corresponding to FIG. 2A to explain a fifth embodiment of the disclosure.

DETAILED DESCRIPTION

A coil component 1 according to a first embodiment of the disclosure is described with reference to FIGS. 1A to 1D.

6

The coil component 1 shown in FIGS. 1A to 1D configures a pulse transformer being an example of a coil component.

As shown in FIGS. 1A to 1D, the coil component 1 includes a drum-shaped core 3 to which a winding core portion 2 is provided. The drum-shaped core 3 also includes a first flange portion 4 and a second flange portion 5 provided at respective end portions of the winding core portion 2 along a predetermined direction D indicated by a double-headed arrow on the right side in FIG. 1B. The drum-shaped core 3 is configured of, for example, a magnetic substance such as ferrite.

The winding core portion 2 has, for example, a substantially circular cylindrical shape or a substantially polygonal cylindrical shape. Unevenness or an inclination may be formed on a surface of the winding core portion 2 if required.

The flange portions 4 and 5 have substantially rectangular parallelepiped shapes having substantially rectangular cross-sectional shapes. The flange portions 4 and 5 respectively have inner end surfaces 4a and 5a that face sides of the winding core portion 2 and position the respective end portions of the winding core portion 2, outer end surfaces 4b and 5b that face outer sides opposite to the inner end surfaces 4a and 5a, bottom surfaces 4c and 5c that face a side of a mount substrate (not shown) at mounting, top surfaces 4d and 5d opposite to the bottom surfaces 4c and 5c, first side surfaces 4e and 5e, and second side surfaces 4f and 5f opposite to the first side surfaces 4e and 5e. The bottom surfaces 4c and 5c, the top surfaces 4d and 5d, the first side surfaces 4e and 5e, and the second side surfaces 4f and 5f couple the inner end surfaces 4a and 5a with the outer end surfaces 4b and 5b, respectively.

The coil component 1 also includes a plate-shaped core 7 bridged between the first and second flange portions 4 and 5 while one principal surface 6 of the plate-shaped core 7 contacts each of the top surfaces 4d and 5d of the first and second flange portions 4 and 5. The plate-shaped core 7 has, for example, a principal surface with a substantially rectangular flat plate shape, and is configured of, for example, a magnetic substance such as ferrite similarly to the drum-shaped core 3. Accordingly, the plate-shaped core 7 configures a closed magnetic path in cooperation with the drum-shaped core 3.

If a first contact portion and a second contact portion are portions which are included in the top surfaces 4d and 5d and which contact the principal surface 6 of the plate-shaped core 7, in the coil component 1, the first contact portion is the entire surface of the top surface 4d, and the second contact portion is the entire surface of the top surface 5d. Therefore, in the following description, it should be understood that the top surface 4d or the top surface 5d also occasionally represents the first contact portion or the second contact portion.

Four first terminal electrodes 8a, 8b, 8c, and 8d are provided in that order on the bottom surface 4c of the first flange portion 4. Four second terminal electrodes 9a, 9b, 9c, and 9d are provided in that order on the bottom surface 5c of the second flange portion 5. In this embodiment, the four first terminal electrodes 8a, 8b, 8c, and 8d have dimensions equivalent to one another, and the four second terminal electrodes 9a, 9b, 9c, and 9d have dimensions equivalent to one another.

The terminal electrodes 8a to 8d and 9a to 9d are formed, for example, by applying a conductive paste containing conductive metal powder such as silver powder, then baking the paste, and further applying nickel plating and tin plating. Alternatively, the terminal electrodes 8a to 8d and 9a to 9d

are formed, for example, by attaching conductive metal pieces formed of copper-based metal, such as tough pitch copper or phosphor bronze, on the flange portions **4** and **5**.

The coil component **1** further includes four wires **11** to **14** wound around the winding core portion **2**. The wires **11** to **14** are formed of, for example, copper lines covered for insulation with resin, such as polyurethane, polyesterimide, or polyamideimide, and each are connected between one of the first terminal electrodes **8a** to **8d** and one of the second terminal electrodes **9a** to **9d**.

The wires **11** to **14** are wound around the winding core portion **2** while a direction along the predetermined direction **D** serves as the winding center axis. Although not shown in detail, the wires **11** to **14** are wound to form two layers on the winding core portion **2**. The two layers include an inner layer on the side that contacts the winding core portion **2** and an outer layer on the outer side of the inner layer. To be more specific, the first wire **11** and the third wire **13** are positioned on the side of the inner layer while being wound by bifilar winding, and the second wire **12** and the fourth wire **14** are positioned on the side of the outer layer while being wound by bifilar winding.

Also, the winding direction of the first wire **11** and the third wire **13** located on the side of the inner layer is opposite to the winding direction of the second wire **12** and the fourth wire **14** located on the side of the outer layer.

One end **11a** of the first wire **11** is connected with the first terminal electrode **8a**. The other end **11b** of the first wire **11** is connected with the second terminal electrode **9b**.

One end **12a** of the second wire **12** is connected with the first terminal electrode **8b**. The other end **12b** of the second wire **12** is connected with the second terminal electrode **9a**.

One end **13a** of the third wire **13** is connected with the first terminal electrode **8c**. The other end **13b** of the third wire **13** is connected with the second terminal electrode **9d**.

One end **14a** of the fourth wire **14** is connected with the first terminal electrode **8d**. The other end **14b** of the fourth wire **14** is connected with the second terminal electrode **9c**.

To connect the above-described wires **11** to **14** with the terminal electrodes **8a** to **8d** and **9a** to **9d**, for example, thermal pressure bonding, ultrasonic welding, or laser welding may be applied.

The coil component **1** having the above-described configuration has the following features.

First, an imaginary quadrangle defined by two vertices **V1** and **V2** on the side of the outer periphery of the top surface **4d** (the first contact portion) of the first flange portion **4** and two vertices **V3** and **V4** on the side of the outer periphery of the top surface **5d** (the second contact portion) of the second flange portion **5** is considered. In FIG. 1A, the positions of the vertices **V1** to **V4** are illustrated. The illustrated positions of the vertices **V1** to **V4** are positions in a perspective view in a direction orthogonal to a direction in which the principal surface **6** of the plate-shaped core **7** extends.

Then, the area of the top surface **4d** (the first contact portion) of the first flange portion **4** and the area of the top surface **5d** (the second contact portion) of the second flange portion **5** are considered. In FIG. 1A, hatching is provided to a region **A1** occupied by the top surface **4d** (the first contact portion) of the first flange portion **4** and a region **A2** occupied by the top surface **5d** (the second contact portion) of the second flange portion **5**.

The sum of the area of the region **A1** and the area of the region **A2** is $\frac{2}{3}$ or larger the area of the imaginary quadrangle defined by the four vertices **V1** to **V4**. In other words, if the imaginary quadrangle is substantially rectangular and the top surfaces **4d** and **5d** are also substantially rectangular

like this embodiment, regarding the dimensions measured in the predetermined direction **D** of the winding core portion **2**, the total sum of dimensions **L1** and **L2** of the top surfaces **4d** and **5d** of the first and second flange portions **4** and **5** is $\frac{2}{3}$ or larger a dimension **L3** of the winding core portion **2**. That is, a condition $L1+L2 \geq L3 \times \frac{2}{3}$ is satisfied. In this embodiment, the area of the region **A1** and the area of the region **A2** are equivalent to each other, that is, the dimensions **L1** and **L2** are equivalent to each other; however, the dimensions **L1** and **L2** may be different from each other.

If this feature configuration is employed, the contact area between the flange portions **4** and **5** and the plate-shaped core **7** can be largely ensured, and hence the magnetic resistance which may be generated between the flange portions **4** and **5** and the plate-shaped core **7** can be decreased.

To be specific, as described above, a gap caused by the unevenness of the top surfaces **4d** and **5d** and the principal surface **6** is generated between the top surfaces **4d** and **5d** of the flange portions **4** and **5** and the principal surface **6** of the plate-shaped core **7**. The gap is configured of the air or resin having a relative magnetic permeability of about 1, and hence has a larger magnetic resistance than those of the drum-shaped core **3** and the plate-shaped core **7** made of the magnetic substance. In terms of the magnetic resistance of the entire closed magnetic path, the magnetic resistance of the gap is dominant.

If the contact area between the flange portions **4** and **5** and the plate-shaped core **7** is increased, the ratio of the gap is relatively decreased, and the magnetic resistance of the closed magnetic path is decreased inversely proportionally to the contact area. Accordingly, in the coil component **1**, the influence of the gap having the large magnetic resistance is relatively decreased at any of the contact surfaces of the flange portions **4** and **5** and the plate-shaped core **7**, and the magnetic resistance which may be generated between each of the flange portions **4** and **5** and the plate-shaped core **7** can be decreased.

Also, the magnetic resistance of the entire closed magnetic path can be decreased accordingly. As the result, a large inductance can be acquired. In other words, even if the same inductance as that of the existing structure is acquired, the winding number of the wires **11** to **14** can be decreased. The same inductance as that of the existing structure can be acquired, and the capacitance and resistance loss can be decreased by the decrease in the winding number of the wires **11** to **14**. Accordingly, the coil component **1** can have good high frequency characteristics.

Further, even if the regions **A1** and **A2** are larger than those of the existing structure, the region between the regions **A1** and **A2** is decreased. When the high frequency characteristics are improved, it is not required to increase the external size as compared with the existing structure. That is, the high frequency characteristics can be improved in case of the equivalent external shape and the same inductance.

To allow the aforementioned advantageous effects to be markedly attained, both the area of the region **A1** and the area of the region **A2** are preferably larger. Hence, the sum of the area of the region **A1** and the area of the region **A2** is, for example, $\frac{5}{6}$ or larger the area of the imaginary quadrangle defined by the four vertices **V1** to **V4**.

Also, the area of the region **A1** is preferably $\frac{1}{2}$ or larger the area of the imaginary quadrangle defined by the vertices **V1** to **V4**, and the area of the region **A2** is also preferably $\frac{1}{2}$ or larger the area of the imaginary quadrangle. Accordingly, the magnetic resistance can be decreased in both the region **A1** and the region **A2**, and the magnetic resistance of the

entire closed magnetic path can be effectively decreased. In this case, the area is the predetermined area or larger preferably for both the region A1 and the region A2. If only one of the region A1 and the region A2 has the predetermined area or larger, it may be occasionally difficult to sufficiently decrease the entire magnetic resistance.

In this embodiment, in the perspective view in the direction orthogonal to the direction in which the principal surface 6 of the plate-shaped core 7 extends, the outer peripheral edge of the plate-shaped core 7 is substantially aligned with the edges of the imaginary quadrangle. Hence, the entire volume of the plate-shaped core 7 can contribute to the formation of the closed magnetic path, and this is efficient. However, if such an advantage is not desirable, for example, the outer peripheral edge of the plate-shaped core 7 may be located outside or inside the edges of the imaginary quadrangle. Like the latter case, an embodiment in which the outer peripheral edges of the plate-shaped core 7 are located inside the edges of the imaginary quadrangle will be described in detail with reference to FIGS. 8 and 9.

The coil component 1 also has the following feature. The first terminal electrodes 8a to 8d are arranged on the bottom surface 4c of the first flange portion 4, to extend from an end edge on the side of the outer end surface 4b toward an end edge on the side of the inner end surface 4a, by a distance L4 which is half or smaller the distance between the outer end surface 4b and the inner end surface 4a (the distance being equivalent to the dimension L1 in this embodiment). Similarly, the second terminal electrodes 9a to 9d are arranged on the bottom surface 5c of the second flange portion 5, to extend from an end edge on the side of the outer end surface 5b toward an end edge on the side of the inner end surface 5a, by a distance L5 which is half or smaller the distance between the outer end surface 5b and the inner end surface 5a (the distance being equivalent to the dimension L2 in this embodiment). That is, conditions $L4 \leq L1 \times \frac{1}{2}$ and $L5 \leq L2 \times \frac{1}{2}$ are satisfied.

If the conditions $L4 \leq L1 \times \frac{1}{2}$ and $L5 \leq L2 \times \frac{1}{2}$ are satisfied, together with the condition that the sum of the area of the region A1 and the area of the region A2 is $\frac{2}{3}$ or larger the area of the imaginary quadrangle determined by the four vertices V1 to V4, a relatively large space in which a terminal electrode is not present can be created near the winding core portion 2, on the side of the bottom surfaces 4c and 5c of the flange portions 4 and 5, that is, on the side of the mount surface. The space in which a terminal electrode is not present near the winding core portion 2 can be used as a buffer space that gives flexibility to the positions and orientations of the wires 11 to 14 between an area on the winding core portion 2 and areas on the terminal electrodes 8a to 8d and 9a to 9d where the positions and orientations of the wires 11 to 14 are fixed. Hence, the wires 11 to 14 are not excessively forcedly deformed, and occurrence of a break or a short in the wires 11 to 14 can be reduced.

Also, if the terminal electrodes 8a to 8d and 9a to 9d are designed to satisfy the conditions $L4 \leq L1 \times \frac{1}{2}$ and $L5 \leq L2 \times \frac{1}{2}$, for example, terminal electrodes with the same dimensions as those of the terminal electrodes formed on the flange portions of the drum-shaped core having the dimensional relationship as described in Japanese Patent No. 4737268 can be arranged at the same positions. Accordingly, when the coil component 1 according to this embodiment is applied, the design of the mount substrate is not required to be changed.

In the drawings, the terminal electrodes 8a to 8d and 9a to 9d are positioned only on the bottom surfaces 4c and 5c of the first and second flange portions 4 and 5; however, part

of the terminal electrodes may be provided to extend to an area on the outer end surfaces 4b and 5b.

Also, in the illustrated coil component 1, the terminal electrodes 8a to 8d and 9a to 9d have the same dimensions; however, it is not limited thereto, and may have different dimensions. Further, in this case, as long as at least one of the terminal electrodes 8a to 8d and 9a to 9d satisfies the condition $L4 \leq L1 \times \frac{1}{2}$ or $L5 \leq L2 \times \frac{1}{2}$, occurrence of a break or a short in the wires 11 to 14 connected with the terminal electrodes can be reduced.

The first and second flange portions 4 and 5 are joined with the plate-shaped core 7, for example, by an adhesive. FIGS. 2A and 2B illustrate a joint structure between the second flange portion 5 and the plate-shaped core 7. The joint structure between the first flange portion 4 and the plate-shaped core 7 not illustrated in FIG. 2A or 2B is substantially similar to the joint structure between the second flange portion 5 and the plate-shaped core 7 illustrated in FIGS. 2A and 2B. Hence, in the following description, only the joint structure between the second flange portion 5 and the plate-shaped core 7 illustrated in FIGS. 2A and 2B is described.

An adhesive 15 is made of, for example, a resin material such as epoxy resin, and is arranged to surround the contact surfaces of the top surface 5d of the flange portion 5 and the principal surface 6 of the plate-shaped core 7 except a portion along the inner end surface 5a. As described above, in the coil component 1, the region A2 being the second contact portion is larger than that of the existing structure, and the outer periphery of the region A2 is long. With this configuration, the adhesive perimeter with the adhesive 15 can be long. Even if the adhesive 15 is arranged to merely surround the contact surfaces, a sufficient adhesive force can be ensured.

Also, as specifically illustrated in FIG. 2B, the adhesive 15 is not present on the contact surfaces of the top surface 5d of the flange portion 5 and the principal surface 6 of the plate-shaped core 7. With this configuration, the state in which the flange portions 4 and 5 directly contact the plate-shaped core 7 can be provided without the adhesive 15 having the larger magnetic resistance than those of the flange portions 4 and 5 and the plate-shaped core 7 interposed therebetween. The magnetic resistance which may be generated between the flange portions 4 and 5 and the plate-shaped core 7 can be decreased. Accordingly, this can contribute to acquisition of a larger inductance.

In FIGS. 1A to 1D, the adhesive 15 is not illustrated.

As described above, since the flange portions 4 and 5 directly contact the plate-shaped core 7, to further decrease the magnetic resistance which may be generated between the flange portions 4 and 5 and the plate-shaped core 7, it is effective to increase the flat properties of the contact surfaces of the flange portions 4 and 5 and the plate-shaped core 7, hence to increase the degree of close contact at the contact surfaces, and to decrease the gap formed between the flange portions 4 and 5 and the plate-shaped core 7. Owing to this, a configuration is employed in which the flat property of each of the top surfaces 4d and 5d of the flange portions 4 and 5 and the principal surface 6 of the plate-shaped core 7 contacting the top surfaces 4d and 5d is higher than the flat property of the other principal surface 16 opposite to the principal surface 6 of the plate-shaped core 7. With this configuration, a region where processing such as mirror-surface polishing is executed to increase the flat property can be minimized.

For the flat property, the surface to be compared with the top surfaces 4d and 5d of the flange portions 4 and 5 and the

11

principal surface **6** of the plate-shaped core **7** which contacts the top surfaces **4d** and **5d** is not limited to the other principal surface **16**, and may be any one of surfaces of the flange portions **4** and **5** and the plate-shaped core **7** except the top surfaces **4d** and **5d** and the principal surface **6**.

A surface having a higher flat property may be only one of the top surfaces **4d** and **5d** of the first and second flange portions **4** and **5**.

In this specification, "flat property" is indicated by, for example, flatness defined in JIS B 0621, or arithmetical mean roughness (line roughness) Ra or arithmetical mean waviness Wa defined in JIS B 0601. In this case, the absolute value of such an index is not important, and the important point is the correlation between the flat properties of the top surfaces **4d** and **5d** and the principal surface **6** and the flat properties of the other surfaces of the drum-shaped core **3**. It is only required to determine whether or not the configuration decreases the magnetic resistance due to the gap.

Next, a coil component **21** according to a second embodiment of the disclosure is described with reference to FIGS. 3A to 3D. The coil component **21** shown in FIGS. 3A to 3D configures a common mode choke coil being an example of a coil component. FIGS. 3A, 3B, 3C, and 3D respectively correspond to FIGS. 1A, 1B, 1C, and 1D. In FIGS. 3A to 3D, like reference signs are applied to elements corresponding to the elements shown in FIGS. 1A to 1D, and redundant description is omitted.

The coil component **21** shown in FIGS. 3A to 3D differs from the coil component **1** shown in FIGS. 1A to 1D for the number of wires. In particular, the coil component **21** includes two wires **11** and **12**. Accordingly, two first terminal electrodes **8a** and **8b** are provided on the first flange portion **4**, and two second terminal electrodes **9a** and **9b** are provided on the second flange portion **5**. One end **11a** of the first wire **11** is connected with the first terminal electrode **8a**. The other end **11b** of the first wire **11** is connected with the second terminal electrode **9a**. One end **12a** of the second wire **12** is connected with the first terminal electrode **8b**. The other end **12b** of the second wire **12** is connected with the second terminal electrode **9b**.

Also, the winding direction of the first wire **11** is the same as the winding direction of the second wire **12**. The first wire **11** and the second wire **12** may be wound by single-layer bifilar winding, or the first wire **11** and the second wire **12** may be wound in two layers so that one of the wires is arranged on the side of the inner layer and the other wire is arranged on the side of the outer layer.

Also, the coil component **21** shown in FIGS. 3A to 3D differs from the coil component **1** shown in FIGS. 1A to 1D for the forms of the flange portions **4** and **5** in the drum-shaped core **3**. In particular, in the coil component **21**, gradient surfaces **22** and **23** are formed at the bottom surfaces **4c** and **5c** of the flange portions **4** and **5** on the sides of the inner end surfaces **4a** and **5a**. The gradient surfaces **22** and **23** can further increase the space in which a terminal electrode is not present formed on the side of the bottom surfaces **4c** and **5c** of the flange portions **4** and **5**, that is, on the side of the mount surface. In addition, a shorter or the shortest path can be given to each of the wires **11** and **12** guided from the end portion peripheral surfaces of the winding core portion **2** to the terminal electrodes **8a**, **8b**, **9a**, and **9b**.

Accordingly, the wires **11** and **12** can be guided from the end portion peripheral surfaces of the winding core portion **2** to the terminal electrodes **8a**, **8b**, **9a**, and **9b** in a more natural state, and hence occurrence of a break or a short in the wires **11** and **12** can be further reduced. Also, since the

12

wires **11** and **12** can be shorter, the capacitance and direct-current resistance loss generated at the wires **11** and **12** can be decreased, and the high frequency characteristics of the coil component **1** can be further improved.

5 It is to be noted that a gradient surface may be provided at only one of the first and second flange portions **4** and **5**.

Next, a coil component **31** according to a third embodiment of the disclosure is described with reference to FIGS. 4A to 4D. The coil component **31** shown in FIGS. 4A to 4D configures a normal inductor being an example of a coil component. FIGS. 4A, 4B, 4C, and 4D respectively correspond to FIGS. 1A, 1B, 1C, and 1D. In FIGS. 4A to 4D, like reference signs are applied to elements corresponding to the elements shown in FIGS. 1A to 1D, and redundant description is omitted.

The coil component **31** shown in FIGS. 4A to 4D differs from the coil component **1** shown in FIGS. 1A to 1D for the number of wires. In particular, the coil component **31** includes only a single wire **11**. Accordingly, a single first terminal electrode **8a** is provided on the first flange portion **4**, and a single second terminal electrode **9a** is provided on the second flange portion **5**. One end **11a** of the first wire **11** is connected with the first terminal electrode **8a**. The other end **11b** of the first wire **11** is connected with the second terminal electrode **9a**.

Also, the coil component **31** shown in FIGS. 4A to 4D differs from the coil component **1** shown in FIGS. 1A to 1D for the forms of the flange portions **4** and **5** in the drum-shaped core **3**. In particular, in the coil component **31**, step surfaces **32** and **33** are formed at the bottom surfaces **4c** and **5c** of the flange portions **4** and **5** on the sides of the inner end surfaces **4a** and **5a**. The step surfaces **32** and **33** attain advantageous effects similar to those of the gradient surfaces **22** and **23** in the coil component **21** shown in FIGS. 3A to 3D.

It is to be noted that a step surface may be provided at only one of the first and second flange portions **4** and **5**.

In any of the coil components **1**, **21**, and **31** according to the above-described embodiments, the flange portions **4** and **5** and the plate-shaped core **7** have substantially rectangular parallelepiped shapes; however, it is not limited thereto, and, may have, for example, shapes with corners chamfered. Also, the shapes of the top surfaces of the flange portions and the principal surface of the plate-shaped core are not limited to substantially rectangular shapes, and may be substantially square shapes, substantially polygonal shapes, substantially circular shapes, substantially ellipsoidal shapes, or combinations of these.

If the shapes of the top surfaces of the flange portions and the principal surface of the plate-shaped core are not substantially rectangular (quadrangular) as described above, "the area to be compared" with the sum of the area of the first contact portion which is included in the top surface of the first flange portion and which contacts the principal surface of the plate-shaped core, and the area of the second contact portion which is included in the top surface of the second flange portion and which contacts the principal surface of the plate-shaped core is properly corrected. For example, in the coil component **1**, the area of the imaginary quadrangle defined by the four vertices **V1** to **V4** expresses a range through which magnetic fluxes densely pass in the plate-shaped core **7**. That is, in the coil component **1**, the sum of the area of the first contact portion and the area of the second contact portion is a certain ratio (in particular, $\frac{1}{3}$) or larger to the area of the range, and the pass region for the magnetic fluxes with the magnetic loss reduced is ensured. Accordingly, a large inductance is acquired.

More generally, the area of the range in which the magnetic fluxes densely pass in the plate-shaped core can be "the area to be compared." To be more specific, when a first maximum width of the first contact portion and a second maximum width of the second contact portion are maximum widths along a direction orthogonal to the predetermined direction, a third maximum width W is a smaller one of the first and second maximum widths. Also, when an edge on the outer side of the first contact portion (the side of the outer end surface) is a first outer edge and an edge on the outer side of the second contact portion (the side of the outer end surface) is a second outer edge, a maximum length L is a maximum distance between the first outer edge and the second outer edge along the predetermined direction. Then, the sum of the area of the first contact portion and the area of the second contact portion may be $\frac{2}{3}$ or larger a product of the third maximum width W and the maximum length L .

FIGS. 5A to 7B show several characteristic values for comparison between a coil component within a range of the disclosure and a coil component outside the range of the disclosure to clarify the superiority of the coil component within the range of the disclosure.

To obtain the characteristic values shown in FIGS. 5A to 7B, pulse transformers were employed as a sample according to an example within the range of the disclosure and a sample according to a comparative example outside the range.

To be more specific, as the sample according to the example, there was prepared a sample having the structure shown in FIGS. 1A to 1D, external dimensions of 4.5 mm (L_3 =length-direction dimension)×3.2 mm (width-direction dimension)×2.8 mm (thickness-direction dimension), and the dimensions L_1 and L_2 shown in FIG. 1B being $L_1=L_2=1.8$ mm.

In contrast, as the sample according to the comparative example, there was prepared a sample having the structure shown in FIG. 1 of Japanese Patent No. 4737268, external dimensions equivalent to those of the example, and the dimensions L_1 and L_2 shown in FIG. 1B being $L_1=L_2=1.0$ mm.

Also, the pulse transformer according to the example and the pulse transformer according to the comparative example were set to have equivalent inductance values.

In FIGS. 5A and 5B, FIG. 5A shows frequency characteristics of an insertion loss $Sdd21$ obtained by a measurement circuit shown in FIG. 5B. The insertion loss $Sdd21$ shown in FIG. 5A represents a ratio of output to input expressed by unit of decibel [dB] obtained by using the measurement circuit shown in FIG. 5B. The example has higher $Sdd21$ (that is, smaller absolute value of minus dB) than the comparative example. That is, it is found that the example has better insertion loss characteristics than the comparative example. Also, it is found that the example has higher resonant frequencies than the comparative example, and hence the example can be used in a higher frequency region.

In FIGS. 6A and 6B, FIG. 6A shows frequency characteristics of a mode conversion $Scd21$ obtained by a measurement circuit shown in FIG. 6B. The mode conversion $Scd21$ shown in FIG. 6A represents a ratio of output to input expressed by unit of decibel [dB] obtained by using the measurement circuit shown in FIG. 6B. The example has lower $Scd21$ (that is, larger absolute value of minus dB) than the comparative example. That is, it is found that the example has better mode conversion characteristics than the comparative example. Also, it is found that the example has

higher resonant frequencies than the comparative example, and hence the example can be used in a higher frequency region.

In FIGS. 7A and 7B, FIG. 7A shows frequency characteristics of a common mode rejection ratio $Scc21$ obtained by a measurement circuit shown in FIG. 7B. The common mode rejection ratio $Scc21$ shown in FIG. 7A represents a ratio of output to input expressed by unit of decibel [dB] obtained by using the measurement circuit shown in FIG. 7B. The example has lower $Scc21$ (that is, larger absolute value of minus dB) than the comparative example. That is, it is found that the example has better common mode rejection characteristics than the comparative example.

Regarding the above-described characteristic values shown in FIGS. 5A to 7B, the result indicative of that of the example is more preferable than the comparative example obtained because, in the example as compared with the comparative example, it is not required to increase the winding number of wire to acquire the equivalent inductance, hence the interline capacitance generated between turns of the wires can be small, and the insertion loss can be small.

In any of the coil components 1, 21, and 31 described with reference to FIGS. 1A to 4D, in the perspective view in the direction orthogonal to the direction in which the principal surface 6 of the plate-shaped core 7 extends, the outer peripheral edge of the plate-shaped core 7 is substantially aligned with the edges of the imaginary quadrangle defined by the vertices V1 to V4. In contrast, in fourth and fifth embodiments described below respectively with reference to FIGS. 8 and 9, the outer peripheral edge of the plate-shaped core 7 is located inside the edges of the imaginary quadrangle.

FIGS. 8 and 9 are illustrations corresponding to FIG. 2A. In FIGS. 8 and 9, like reference signs are applied to elements corresponding to the elements shown in FIG. 2A, and redundant description is omitted.

In each of the embodiments shown in FIGS. 8 and 9, since the outer peripheral edge of the plate-shaped core 7 is located inside the edges of the imaginary quadrangle, an exposed portion 41 that is exposed from the plate-shaped core 7 is given to the top surface 5d of the flange portion 5 of the drum-shaped core 3. The adhesive 15 is arranged to surround the contact surfaces of the top surface 5d (the second contact portion) of the flange portion 5 and the principal surface 6 of the plate-shaped core 7 while the adhesive 15 contacts the exposed portion 41 and the side surface of the plate-shaped core 7, except for the portion along the inner end surface 5a of the flange portion 5.

With the above-described configuration, the adhesive perimeter with the adhesive 15 can be long, and the adhesive 15 forms a fillet. Hence, the adhesive 15 can contact two surfaces directed in mutually different directions in a cross section. Owing to this, with the configurations shown in FIGS. 8 and 9, a higher adhesive force can be obtained as compared with the configuration shown in FIG. 2A.

In particular, in the embodiment shown in FIG. 9, an outer peripheral edge of the plate-shaped core 7 on the side of the principal surface 6 is chamfered, and a gradient surface 42 is formed along the outer peripheral edge. Hence, the adhesive 15 can be arranged to fill a recessed portion defined by the gradient surface 42 and the top surface 5d of the flange portion 5. As compared with the configuration shown in FIG. 8, a further high adhesive force can be obtained.

Although the description is omitted, the joint structure between the first flange portion 4 and the plate-shaped core 7 not illustrated in FIG. 8 or 9 is preferably substantially

15

similar to the joint structure between the second flange portion **5** and the plate-shaped core **7** illustrated in FIGS. **8** and **9**. However, it is not limited thereto. For the joint structure between the first flange portion **4** and the plate-shaped core **7**, the joint structure shown in FIGS. **2A** and **2B** ⁵ may be employed.

Also in the embodiments shown in FIGS. **8** and **9**, although not shown, as shown in FIG. **2B**, it is preferable that the adhesive **15** is not present on the contact surfaces of each of the top surface **4d** (the first contact portion) of the first flange portion **4** and the top surface **5d** (the second contact portion) of the second flange portion **5**, and the principal surface **6** of the plate-shaped core **7**. ¹⁰

As a modification of the embodiments shown in FIGS. **8** and **9**, part of the adhesive **15** may be arranged to extend to areas on the outer end surfaces **4b** and **5b**, the first side surfaces **4e** and **5e**, and the second side surfaces **4f** and **5f** of the flange portions **4** and **5**. Also, as a modification of the embodiment shown in FIG. **9**, part of the adhesive **15** may be arranged to extend over the gradient surface **42** to areas ¹⁵ on the side surfaces of the plate-shaped core **7**. ²⁰

The coil component according to the disclosure has been described above on the basis of the specific embodiments; however, the embodiments described above are merely examples, and partial replacement and combination are available for the configuration among the different embodiments. For example, the gradient surfaces **22** and **23** shown in FIG. **3B**, or the step surfaces **32** and **33** shown in FIG. **4B** may be employed in the coil component **1** shown in FIGS. **1A** to **1D**. ²⁵

While some embodiments of the disclosure have been described above, it is to be understood that variations and modifications will be apparent to those skilled in the art without departing from the scope and spirit of the disclosure. The scope of the disclosure, therefore, is to be determined solely by the following claims. ³⁰

What is claimed is:

1. A coil component comprising:

a drum-shaped core including a winding core portion and first and second flange portions provided at respective end portions of the winding core portion along a predetermined direction, ⁴⁰

each of the first and second flange portions having an inner end surface that faces a side of the winding core portion and positions the corresponding end portion of the winding core portion, an outer end surface that faces an outer side opposite to the inner end surface, a bottom surface that couples the inner end surface with the outer end surface and faces a side of a mount substrate at mounting, and a top surface opposite to the bottom surface; ⁴⁵

a plate-shaped core bridged between the first and second flange portions while one principal surface of the plate-shaped core contacts the top surface of each of the first and second flange portions; ⁵⁰

at least one first terminal electrode provided on the bottom surface of the first flange portion;

at least one second terminal electrode provided on the bottom surface of the second flange portion; and

at least one wire wound around the winding core portion and connected between the first and second terminal electrodes, ⁵⁵

wherein a sum of an area of a first contact portion which is included in the top surface of the first flange portion and which contacts the one principal surface of the plate-shaped core and an area of a second contact portion which is included in the top surface of the ⁶⁰

16

second flange portion and which contacts the one principal surface of the plate-shaped core is $\frac{2}{3}$ or larger a product of a third maximum width **W** and a maximum length **L**, in a case where, when a first maximum width of the first contact portion and a second maximum width of the second contact portion are maximum widths along a direction orthogonal to the predetermined direction, the third maximum width **W** is a smaller one of the first maximum width and the second maximum width, and in a case where, when an edge on the outer side of the first contact portion is a first outer edge and an edge on the outer side of the second contact portion is a second outer edge, the maximum length **L** is a maximum distance between the first outer edge and the second outer edge measured along the predetermined direction.

2. The coil component according to claim 1,

wherein the first and second contact portions are substantially quadrangular; and

wherein the sum of the area of the first contact portion and the area of the second contact portion is $\frac{2}{3}$ or larger an area of an imaginary quadrangle defined by two vertices on a side of an outer periphery of the first contact portion and two vertices on a side of an outer periphery of the second contact portion.

3. The coil component according to claim 2, wherein, in a perspective view in a direction orthogonal to a direction in which the principal surface of the plate-shaped core extends, an outer peripheral edge of the plate-shaped core is substantially aligned with edges of the imaginary quadrangle.

4. The coil component according to claim 3, wherein the first and second flange portions are joined with the plate-shaped core by an adhesive, and the adhesive is arranged to surround contact surfaces of the first and second contact portions of the first and second flange portions and the principal surface of the plate-shaped core, except for portions along the inner end surfaces.

5. The coil component according to claim 2, wherein, in a perspective view in a direction orthogonal to a direction in which the principal surface of the plate-shaped core extends, an outer peripheral edge of the plate-shaped core is located inside the imaginary quadrangle, and hence an exposed portion exposed from the plate-shaped core is provided at each of the top surfaces of the first and second flange portions.

6. The coil component according to claim 5, wherein the first and second flange portions are joined with the plate-shaped core by an adhesive, and the adhesive is arranged to surround contact surfaces of the first and second contact portions of the first and second flange portions and the principal surface of the plate-shaped core, except for portions along the inner end surfaces while the adhesive contacts the exposed portions and side surfaces of the plate-shaped core.

7. The coil component according to claim 4, wherein the adhesive is not present on the contact surfaces of each of the first and second contact portions of the first and second flange portions and the principal surface of the plate-shaped core.

8. The coil component according to claim 1, wherein at least one of the first and second terminal electrodes is arranged to extend from an end edge on a side of the outer end surface toward an end edge on a side of the inner end surface on the bottom surface of the first or second flange portion by a distance of half or smaller a distance between the outer end surface and the inner end surface.

17

18

9. The coil component according to claim 8, wherein a gradient surface or a step surface is formed on the side of the inner end surface on the bottom surface of at least one of the first and second flange portions.

10. The coil component according to claim 1, wherein a flat property of the top surface of at least one of the first and second flange portions is higher than a flat property of another principal surface opposite to the principal surface of the plate-shaped core. 5

11. The coil component according to claim 1, wherein a flat property of the principal surface of the plate-shaped core which contacts each of the top surfaces of the first and second flange portions is higher than the flat property of the other principal surface opposite to the principal surface of the plate-shaped core. 10

12. The coil component according to claim 6, wherein the adhesive is not present on the contact surfaces of each of the first and second contact portions of the first and second flange portions and the principal surface of the plate-shaped core. 15

20
